PAINTER'S EASEL

Winfred N. Lurcott, Elizabeth, N. J.

Application January 25, 1932, Serial No. 588,571

3 Claims. (Cl. 45—129)

Among the principal objects which the present invention has in view are: To economize in floor space when the easel is in service; to increase the durability of the easel; to provide means for arranging canvasses during application of paint thereto; to accommodate the light in which the same are being painted; to furnish a bench for holding various articles when not employed; to provide an adjustable picture lighting attachment for said easel; and to facilitate the transportation or movement of the easel when shifting the location thereof.

Drawing:

Figure 1 is a front view of an easel constructed and arranged in accordance with the present invention.

Figure 2 is a side view of the same.

Figure 3 is a detailed view in vertical section of a fragment of the main standard of the lower supporting bracket and of bench or table with which the base is equipped.

Figure 4 is a top plan view showing fragments of the bracket for holding the table with which the easel is provided and adjustable supporting ring therefor.

Description:

The easel is primarily designed to supply the needs of what is known as class-room easels. To this end a metallic tube or pipe section 8 is suitably mounted in a low tripod 9, a threaded boss 10 being preferably employed therefor.

The tripod 9 has two rearwardly extending relatively short legs 11 and a relatively heavy and somewhat elongated forwardly extending leg 12.

Each of the legs 11 has a serrated foot 14 which overcomes any tendency on the part of the easel to slide when in service. Each of the said legs has mounted thereon, wheels 15. The wheels 15 are so disposed that the periphery thereof is removed from floor when the easel is in service position as when the tube 8 is vertically disposed. When the easel is tilted backwards, the wheels 15 are brought in contact with the floor and the feet 14 are lifted therefrom. In this position it is obvious the easel can be trundled or rolled to any desired location, where, by setting the easel upright, the wheels 15 are removed from the floor and the easel is disposed in established position.

To overcome any tendency for the easel to topple backwards, the leg 12 which extends to the front of the easel in service is furnished with a heavy weighted foot member 16. The weight of the foot member 16 overcomes any inclination of the easel to tilt backwards.

Mounted in adjusted positions upon the tube 8 is a canvas supporting bracket 17. The bracket 17 has two extended and separated arms each being provided with a series of curved receptacles 18.

The canvas on which an artist is to paint sets within the receptacles 18, the bottom of said canvas being moved toward the front or back at will.

The bracket 17 is provided with a wedge member 19 integrally formed therewith. The wedge member 19 has a concave surface which fits the tube 8 snugly. Said member is also provided with a socket to receive the end of a thumb screw 20, as best seen in Fig. 3 of the drawing. The screw 20 is extended through a tapped perforation in an oval ring 21.

By means of this construction it will be seen that whenever the screw 20 is set up, the wedge 19 is pressed hard against the tube 8 to frictionally grip the same. It will also be seen that all weight imposed upon the bracket 17 has a tendency to force the wedge tightly against the tube 8.

In service the canvas is held between the lower bracket 17 and an upper bracket 22. The upper bracket 22 has extended arms on which the curved receptacles 23 are formed. These are adapted to overhang and hold the edge of the canvas thereunder. This bracket is free to move up and down upon the tube 24.

The tube 24 is preferably of sufficient length to extend to adjacent the bottom of the tube 8, when the pipe T 25 with which the said tube is provided rests upon the collar 26 of the bracket 22 and when the said bracket is in its lowest position as shown in Figure 2, of the drawing.

The tube 24 is held in adjusted position by means of a thumb screw 27. The adjustment thus afforded provides for the arrangement of 40 the extension arm 28 which carries an electric lighting bulb 29 and reflector 30 therefor. The bulb 29 and reflector 30 are provided to throw light upon a canvas being worked upon. The current for the bulb 29 is delivered through the 45 wires 40 equipped with a switch 31.

From the above it will be seen that in service canvases of various sizes may be mounted in various positions to be held between the brackets 17 and 22. It will also be seen that the lighting attachment carrying the bulbs 29 may be adjusted to suit the canvas mounted between the said brackets. It will also be noted that the canvas can be tilted in the said brackets to suit the desires of various artists and the exigencies 55

of light in the various locations. The extension arm 28 may be moved in and out in front of the canvas to be firmly secured in position by the thumb screw 32.

5. The easel is equipped with a removable table 33 provided to hold brushes and various accessories or equipments with which the artist is working.

The table 33 is provided with a bracket 34 at 10 the end of which a grappling hook 35 is mounted, which hook as shown best in Figure 4 has arms 36 that extend under a supporting ring 37, in the upper surface whereof a groove is formed to receive the hook 35.

15. When the table 33 is adjusted in working position upon the ring 37, it will be found that the table can be moved freely around the tube 8 as far as permitted by the set screw 38 which extends through the ring 37 to engage the said tube in a frictional grip.

20. When desired to disengage the table 33 from the ring 37, it becomes only necessary to lift the forward end of the said table to free the arms 36 from the ring 37 when the hook 35 may be lifted from the groove 39 in the ring 37.

25. It will be observed that the parts constituting the present easel may be dissociated and packed within small compass for travel, transportation or storage, to be readily and quickly reassembled when desired for service.

30. It will also be observed that the floor space occupied by the legs 12 and 13 is relatively small as compared with the floor space occupied by most easels.

35. Also it will be noted that the structure when in service will not interfere with the view of other artists or students working about a given object as is customary in art schools.

I claim:

40. 1. An artist's easel comprising an easel embodying telescopic members; a canvas supporting bracket slidably mounted on one of said members; means for maintaining said bracket in adjusted position; a second bracket for engaging the upper edge of a canvas when supported by the first mentioned bracket; a supporting base

for said standard embodying a plurality of legs, one of said legs projecting therefrom in the same general direction as the brackets so as to underlie the same and being weighted to maintain the working position of said easel, and certain of said legs having rolling members for trundling said easel and parts associated therewith; and means associated with said legs in juxtaposed relation to said rolling members for lifting said rolling members from service position when said easel is in vertical position.

5. An artist's easel comprising an easel embodying telescopic members; a canvas supporting bracket slidably mounted on one of said members; means for maintaining said bracket in adjusted position; a second bracket for engaging the upper edge of a canvas when supported by the first mentioned bracket; a supporting base for said easel embodying a plurality of legs, one of said legs projecting therefrom in the same 10 general direction as the brackets so as to underlie the same and being weighted to maintain the working position of said easel; and certain of said legs having rolling members for trundling said easel and parts associated therewith; and means associated with said legs in juxtaposed relation to said rolling members for lifting said rolling members from service position when said easel is in vertical position, said means embodying a plurality of feet integrally formed with 15 their associated legs and adapted to lift said wheels from their supporting relation to said easel.

3. An artist's easel comprising an upright portion and a tripod supporting said upright portion, 20 brackets on said upright portion projecting laterally therefrom, said tripod having a leg projecting therefrom in the same general direction as said brackets so as to underlie the same and to receive downward pressure transmitted in use to the brackets thereby preventing the easel from tilting forwardly, the same leg likewise being weighted to prevent normal pressures applied from the front toward the upright portion from 25 tilting the easel backward.

WINFRED N. LURCOTT.
